ILLUMINATED CANE

Filed Oct. 1, 1937

UNITED STATES PATENT OFFICE

2,144,858

ILLUMINATED CANE

Glenn Alan Smith, Montesano, Wash.

Application October 1, 1937, Serial No. 166,785

1 Claim. (Cl. 240—6.42)

This invention relates generally to an illuminating means, and particularly to an illuminating cane or the like.

The main object of this invention is the provision of an exceedingly simple and efficient form of walking cane and an electric lamp adapted to flash intermittently as the cane contacts the ground or to be illuminated continuously as desired.

I accomplish this and other objects in the manner set forth in the specification following as illustrated in the accompanying drawing, in which:

Fig. 1 is a fragmentary longitudinal section through the device.

Fig. 2 is an enlarged longitudinal section through the ground engaging end of the cane.

Fig. 3 is a section taken along the line 3—3 in Fig. 1.

Fig. 4 is a fragmentary section of the ground engaging end of the cane showing the parts in position to energize the lamp.

Fig. 5 is an elevation of the ground engaging end of the cane showing a portion of the outer sleeve broken away in section.

Fig. 6 is a transverse section taken along the line 6—6 in Fig. 1.

Similar numerals refer to similar parts throughout the several views.

Referring in detail to the drawing, there is shown a handle 10 which projects into the enlarged end 11 of a tube 12. The enlarged portion 11 has formed therein the window openings 13 in which is disposed the electric lamp 14 which is mounted in the socket 15 on the dividing wall 16. Within the tube 12 are placed a series of batteries 17. The battery 17 nearest the lamp 14 has its terminal 18 in engagement with the contact 19 of the socket 15.

The lower end of the tube 12 is provided with the downwardly extending lugs 20. A tubular cap 21 is slidably mounted on the lower end of the tube 12. The cap 21 has a closed end 22 having a tubular tip 23. On the inner side of the cap 21 are formed the longitudinal ribs 24 which are diametrically opposite. In the upper end of the cap 21 are formed the bayonet slots 25 having the single left hand extension 26 and the right hand extensions 27 and 28. Projecting from the tube 12 are the bayonet pins 29.

Within the cap 21 is disposed a plunger 30 from whose lower end extends the ground engaging tip 31 which projects through the tubular tip 23. The plunger 30 is provided with lateral grooves 32 and the upwardly extending lugs 33.

Within the plunger 30 is placed a spring 34 whose upper end is provided with an insulated bushing 35. The ground engaging tip 31 has provided at

its upper end a spring urged contact 36 and the bushing 35 normally extends above the upper end of the contact 36.

In this form of the device, when the parts are in the position shown in Fig. 1, the member 31 is extended and the contact 36 is not in engagement with the lowermost battery cell 17, therefore no current flows to the lamp 14. If, however, the cane is pressed downwardly causing the contact 36 to engage the cell 17 as shown in Fig. 4, current does flow to the lamp 14 causing it to be energized.

It will be noted that normally the bayonet pin 29 occupies the slot 28 which permits the plunger 30 to move with relation to the tube 12 whenever the tip 31 engages the ground with sufficient force to compress the spring 34. If, however, the cap 21 is moved to a position in which the pin 29 occupies the slot 27, then the lamp 14 is continuously energized. On the other hand if the pin 29 occupies the slot 26, it brings the parts to the position shown in Fig. 5 wherein the lugs 33 are in alignment with the lugs 20 and the plunger 30 cannot move longitudinally with relation to the member 12. That is to say, the lamp 14 cannot be energized since the contact 36 cannot engage the battery cell 17.

While I have referred to this device as a cane, it must be understood that the invention is equally applicable to umbrellas, swagger sticks and other similar objects.

It is desirable to surround the lamp 14 with a transparency 50 which is preferably colored.

I claim:

A cane having in combination a tubular battery cell holder having dry cells mounted therein and having an electric lamp connected to said cells, said tube having lateral openings therein for emitting light from said lamp, a tubular cap on the lower end of said tube having a bayonet fastening thereto adapted to hold said cap in either of two longitudinal positions or either of two rotary positions, the lower end of said tube having a pair of lugs projecting therefrom, a plunger in said cap also having lugs projecting therefrom, said plunger lugs being adapted to register with the first mentioned lugs when said bayonet connection is turned in one direction and to pass same when said bayonet connection is turned in the opposite direction, a spring for urging said plunger away from said tube, a ground engaging tip attached to said plunger and projecting downwardly through said cap and a yieldable contact mounted in said plunger adapted to engage the lowermost battery when said ground engaging tip is pressed against an object.

GLENN ALAN SMITH.
